UNITED STATES PATENT OFFICE.

JAMES M. HOPKINS, OF CHICAGO, ILLINOIS, ASSIGNOR TO Q. & H. COMPANY, OF CHICAGO, ILLINOIS, A CORPORATION

HANGER FOR CAR-DOOR RAILS.

No. 889,011:

Specification of Letters Patent.

Patented May 26, 1908.

Application filed December 14, 1907. Serial No. 406,417.

To all whom it may concern:

Be it known that I, JAMES M. HOPKINS, a citizen of the United States, and a resident of Chicago, county of Cook, and State of Illinois, have invented certain new and useful Improvements in Hangers for Car-Door Rails, of which the following is a specification.

The invention relates to means for slidably supporting car-doors, and more particularly to means for supporting the rails on which the car-door slides or with which the hangers of the door engage. In present constructions, these rails are usually held in place by bolts, or by bolts having offsetting sleeves thereon to hold the rails in proper position. Such supporting bolts often work loose in the parts through which they extend, so that the rail, which supports the door, sags or gets out of true position and the door binds and cannot be readily shifted back and forth.

The present invention seeks to provide means for rigidly supporting the rail which carries the weight of the car-door in such a manner that it cannot readily work loose or get out of its true, horizontal position.

The invention consists in the features of construction, combinations and arrangement of parts hereinafter set forth, illustrated in the accompanying drawings and more particularly pointed out in the appended claims.

In the drawings, Figure 1 is a view in elevation of parts of the car door and car frame adjacent the upper edge of the door to which the present improvement is applied. Fig. 2 is a view in section of parts shown in Fig. 1. Fig. 3 is a view in section illustrating a slightly modified form of the supporting bracket for the door-rails. Fig. 4 is a view similar to Fig. 1 illustrating the application of the invention to a different form of car door hanger and rail. Fig. 5 is a vertical section at one side of the hanger of Fig. 4.

The parts of the car door and frame illustrated are of usual construction. The car door hanger 1 is secured to the upper edge 50 of the door 2 by bolts 3. The upper portion of the hanger projects above the upper edge of the door and, in the form shown in Figs. 1 and 2, is shaped to form a hood or casing 4 within which is journaled a roller 5. This 55 roller runs upon the central horizontal web

of a Z-shaped rail 6. The door is held against lateral displacement by an L-shaped projection or finger 7 which engages the depending flange 8 at the outer edge of the rail 6.

The upwardly projecting flange 9 at the inner edge of the rail abuts against the siding 10 below the facia 11. In prior constructions the rail has been secured in place solely by a series of bolts 13 extending through the flange 9, siding 10, and the car-plate or roof beam 12. As stated, these bolts tend to work loose so that the rail which sustains the entire weight of the door sags and the door itself binds or can be shifted only with difficulty. This loosening of the bolts is brought about by the transverse strain thereon due to the weight of the car-door upon the rail. In accordance with the present invention, supporting brackets or hangers are provided for the door-rail and these brackets are hung or suspended from the plate 12 or other portion of the car frame, so that the fastener bolts 13 are relieved of the transverse strain due to the pressure of the door-hangers upon the rail.

In the form shown in Figs. 1, 2 and 3, the supporting bracket or hanger 14 is provided at its lower end with a suitable seat for receiving or engaging the Z-shaped rail. This is preferably formed by an outwardly projecting finger 15 that extends below the horizontal web portion of the rail and a depending finger 16 then engages the upstanding flange 9 at the inner edge of the rail. In other words, the bracket is provided at its lower end with a slot for receiving the flange 9. At its upper end the bracket is provided with an inwardly-projecting portion which rests upon the upper edge of the car plate 12, and which is preferably, as shown, recessed into the upper face of the plate. This projection is preferably hook-shaped or provided at its inner end with a depending lug 18 which engages the inner face of the plate 12, as shown in Fig. 2, or which may be sharpened, as shown at 18' in Fig. 3, and forced into the body of the plate or into a recess formed therein. While this arrangement is preferred in a wooden car, it will be understood that the bracket or hanger could be suspended from some portion of the car-frame other than the plate.

The upright portion of the bracket 14 preferably abuts snugly against the outer

face of the car-plate 12 and to permit this arrangement, the siding 10 is cut away at points where the brackets are located. The siding, however, snugly abuts against the 5 sides of the brackets 14 so that they are securely held against displacement in lateral direction. Each bracket is also preferably held in place by a heavy wooden screw 19 extending through the upright portion of 10 the bracket into the wooden plate 12. The fastener bolts 13 extend through the flange 9 of the rail and through the plate 12, as shown, so that the parts are securely held against displacement in outward direction. 15 The fastener bolts 13 are entirely relieved of strain in vertical direction due to the weight of the door upon the car-rail by the supporting brackets or hangers which securely hold the rail in proper position and which cannot 20 become loosened by the rough usage to which car-doors are usually subjected. The facia strip 11 extends over the brackets 14 as indicated at Figs. 2 and 3 and aids in holding them in place. 25 In Figs. 4 and 5 the application of the invention to a different form of door hanger and rail is illustrated. In this form the door hanger 1' carries, at its upper hooked end 4' the grooved roller 5' which runs upon 30 the upper edge of a flat rail 6'. The construction of the supporting bracket 14' is similar to that shown in Figs. 1, 2 and 3, except that it is provided at its lower end with a forwardly projecting part 20 having a 35 pending lug 21 and which lug is provided with a vertical slot or seat for the rail 6'. In this form the vertical portion of the bracket abuts against the face of the siding 10 and is recessed in the facia strip 11', so that the 40 latter is securely held against lateral displacement. The bracket, as shown, is preferably provided with a triangular strengthening flange 22 between its vertical portion and the projection 20. The fastener bolts 45 13' extend through the rail 6', facia 11', siding 10 and the plate 12. As in the other form described the vertical strain upon the rail is carried by the supporting brackets or hangers which are securely suspended from

the plate 12 or other portion of the car frame. 50 The invention thus provides efficient and durable means for holding the door rail in true position so that the car doors may be shifted easily.

It is obvious that numerous changes may 55 be made in the details set forth and that the improvement may be adapted to different types of cars and car doors without departure from the essentials of the invention as defined in the claims.

Having described my invention, what I 60 claim as new, and desire to secure by Letters Patent, is:—

1. A supporting bracket for car-door rails having a hook-shaped portion at the upper 65 end, whereby the bracket can be suspended from a portion of the car-frame, substantially as described.

2. A supporting bracket or hanger for car door rails having at its upper end an angularly 70 turned portion adapted to overlap and interlock with a portion of the car frame and having a seat for the rail.

3. A supporting bracket for car-door rails having a hook-portion at its upper end and a 75 forwardly projecting part at its lower end provided with a rail seat, substantially as described.

4. The combination with the car-plate and the door-rail, of a supporting bracket having 80 an inwardly projecting hook-portion at the upper end for engaging the car-plate to suspend the bracket therefrom, and having a seat for receiving the rail at the lower end, substantially as described.

5. The combination with the car-plate and the Z-shaped door - rail, of a supporting bracket having a hook-portion at the upper end for engaging the car-plate and provided at its lower end with a projection extending 90 outwardly beneath the rail and with a slot engaging the inner edge flange thereof, and bolts extending through the rail and plate, substantially as described.

JAMES M. HOPKINS.
